TELEVISION CART

Walter Gusdorf, 1042 Orchard Lakes, Creve Coeur, Mo.

Filed Jan. 24, 1964, Ser. No. 78,352

Term of patent 7 years

(Cl. D33—14)

FIG.1

FIG.3

FIG. 1 is a front elevational view of a television cart showing my new design;

FIG. 2 is a side elevational view taken at the right side of FIG. 1 showing my design in full line; and

FIG. 3 is a perspective view of the television cart showing the opposite side thereof, my design being shown in full line.

The dominant features of my design reside in those portions shown in full lines in the drawing.

I claim:

The ornamental design for television cart, substantially as shown and described.
